ASSIGNORS OF ONE-THIRD TO ROBERT DOW, OF PAWTUCKET, RHODE ISLAND.

LOOM.

1,055,191.

Specification of Letters Patent. Patented Mar. 4, 1913.

Application filed July 27, 1912. Serial No. 711,844.

To all whom it may concern:

Be it known that we, STANISLAUS LEDOUX and JOSEPH TURCOTTE, citizens of the United States, residing at Pawtucket, in the county of Providence and State of Rhode Island, have invented a new and useful Improvement in Looms, of which the following is a specification.

This invention relates to certain new and useful improvements in looms, and relates more particularly to an improved device for introducing a cord in what is known as leno or cross-weaving.

The object of the invention is to provide a simple and economical mechanism for the purpose above set forth, in which the number of cords, depending upon the peculiarity of the weave, may be readily varied as desired.

20 In the drawings: Figure 1 is a side elevation of the invention. Fig. 2 is a fragmentary perspective view. Figs. 3 and 4 are detail fragmentary side elevations showing two positions of the disks that carry the 25 cords, and Fig. 5 is an enlarged detail side elevation of one of the cord carrying disks.

Each side of the loom frame is designated 1 in the drawings, and has an inverted U-shaped bracket 2 secured thereto, this especially shape of bracket being employed in order to accommodate and permit of free play of the rods 3 that connect the lay 4 with the crank shaft 5 to operate the latter during the process of weaving. To the brackets 2 30 horizontal slotted arms 6 are adjustably secured by bolts 7 the bolts passing through the slots of the arms. A bearing plate 8 is secured to the outer end of each arm 6 the plates 8 supporting a shaft 9. Shaft 9 extends throughout the entire width of the loom and carries a spring rod 10, which latter is disposed parallel to the shaft and has its ends secured thereto. Shaft 9 and rod 10 are provided with a series of alining notches 35 that receive the end walls formed by the key-hole shaped slots 11 of the cord carrying disks 12. A pulley 13 is secured to an end of the shaft 9 and has two straps secured thereto, one of which straps 14 is connected 40 to the jack 15 to be operated by the pattern chain, thereby to partially revolve the shaft 9. The other strap 16 is connected by a coiled spring 17 to the floor, whereby the 45 spring will return the shaft 9 to normal position after partial rotation thereof. Each 50 disk 12 is formed with a half-moon like shaped opening 18 which provides a semi-circular rim 19 which is provided with a central aperture 20 through which a cord 21 passes. A second cord 22 extends through 55 the space 18.

The operation is as follows: The to and fro movement of the jack 15 causes corresponding movement of the strap 14, and the latter partially rotates the shaft 9 through 60 the intermediary of the pulley 13, the shaft upon outward movement of the jack being restored to normal position by means of the strap 16 and the spring 17, thus imparting to the shaft by the means just mentioned a rotary reciprocatory or alternating rotary movement. Since the disks 12 are mounted on the shaft 9, they partake of its stated movement, thus causing the disks to assume the two extreme positions depicted in Figs. 3 and 4 of the drawings. 65 When the disks are in the position shown in Fig. 4, the yarn 21 is depressed, thus causing same to cross over the yarn 22 that extends through the openings 18, bringing 70 the yarn 22 to the surface of the goods being woven, and when the shaft 9 is returned to normal position the yarn 21 will be brought to the surface to be woven into the goods, as shown in Fig. 3 of the drawings. 75 The raising of the yarn 22 to the position illustrated in Fig. 4 of the drawings is due to the fact that the opening 18 forms a shouldered abutment 23, which effects upward movement of the yarn. The disks 12 80 it will be noted can, by mere inward movement of the rod 10, be moved to any position along the shaft, where they will be effectively held in the notches of the rod and shaft by the tension exerted by the 85 spring rod 10, and it will further be apparent that any number of disks may be placed in the shaft, by simple notching of the latter and the spring rod, to accommodate the number to be used.

100 In some looms it is not necessary to employ U-shaped brackets 2, other formations being permissible.

Having thus described our invention, we claim as new and desire to secure by Letters 105 Patent:—

1. In combination with a loom frame, a pair of inverted U-shaped brackets secured

thereto, a horizontal adjustable arm carried by each bracket, a bearing plate secured to each arm, a shaft carried by said plates, a pulley on one end of the shaft, a strap connected to one side of the pulley and to the jack, a second strap connected to the opposite side of the pulley, a coiled spring connected to the second strap and to the floor, a spring rod parallel with and connected to 10 said shaft, said rod and shaft being provided with a series of alined notches, and disks on the shaft formed with apertures to receive said rod and shaft, said disks having openings which provide shouldered 15 abutments and rims and each further having a central yarn aperture in the rim thereof.

2. The combination with a loom, a shaft, disks on the shaft formed to each engage 20 a pair of cords, spring means to hold the disks on the shaft, and means for imparting alternating rotary movement to said shaft whereby to alternately raise said cords to the surface of the goods to be woven into the 25 same.

3. In combination with a loom, a shaft, means to impart alternating rotary movement to said shaft and a series of spring held devices adjustable on said shaft each 30 formed to engage a plurality of cords and to alternately move same to a position for

weaving into the goods by raising and lowering the cords.

4. In combination with a loom, a shaft, means to impart alternating rotary movement to said shaft, and a series of disks rigidly mounted on said shaft each formed 35 with an opening that provides a rim and a shouldered abutment, the rim having a central aperture to receive a cord, said opening 40 being for the reception of a second cord that engages said shouldered abutment.

5. In a loom, a notched shaft, a notched rod carried by the shaft, a series of yarn engaging elements apertured to receive said 45 shaft and rod to engage in the notches thereof, and means to actuate the shaft.

6. In a loom, a shaft, a spring rod carried by the shaft, and a plurality of yarn engaging elements formed to receive said 50 shaft and rod and to be held in frictional engagement therewith by virtue of the tension exerted by said spring rod.

In testimony whereof we have signed our names to this specification in the presence 55 of two subscribing witnesses.

STANISLAUS LEDOUX.
JOSEPH TURCOTTE.
